COMBINATION BOILER TUBE BLOWER

Filed Aug. 29, 1927

FIG. 1.

FIG. 2.

Inventor

DAVID YOUNG

By *Eugene E. Terence* Attorney

UNITED STATES PATENT OFFICE

DAVID YOUNG, OF NEWARK, NEW JERSEY

COMBINATION BOILER TUBE BLOWER

Application filed August 29, 1927. Serial No. 216,299.

This invention relates to apparatus for cleaning boiler tubes particularly those coated with soot and more particularly to a portable apparatus adaptable for cleaning vertical tubes either from the top or the bottom and for cleaning horizontal tubes in vertical and horizontal boilers respectively.

Known device cannot be quickly placed in proper position for cleaning the tubes at the top crown of vertical boilers due to the positions of the mountings, fittings, fixtures, and pipes nor can they be readily attached to or separated from the source of steam or compressed air by means of which the cleaning is effected. Such devices are, moreover, not adaptable to horizontal tubes nor for cleaning vertical tubes from the bottom.

The present invention overcomes all these disadvantages and presents additional advantages peculiar to its construction. It is adaptable to horizontal tubes and for cleaning vertical tubes from the bottom. It is portable, readily placed in position, easily and quickly connected to or separated from the source of steam or compressed air, and otherwise admirably adapted to perform the functions for which it was designed.

Reference is made to the accompanying drawings wherein:

Figure 1 is a view of a form of the apparatus for cleaning horizontal boiler tubes;

Figure 2 is a side elevation of an attachment used for cleaning vertical tubes from the bottom.

Similar numerals refer to similar parts throughout the several views.

Referring now particularly to the drawings, 1 is a pipe having a coupling 2 on its rearward end by means of which connection is made to the source of steam or compressed air. On the forward end is a four-way fitting 3 and intermediate the ends is a valve 4 whereby the steam or compressed air can be suitably controlled.

Suitably united to the pipe 1 are handles 5 and 6, as shown, so that the apparatus may be appropriately directed and guided.

These elements are common to both modifications of the invention shown in Figs. 1 and 2. The device shown in Fig. 1 is particu-

larly adapted to serve the purpose of cleaning horizontal boiler tubes and comprises a readily removable attachment associated with the hereinbefore mentioned elements common to both modifications of the invention. This attachment comprises a blower head 9 surrounded by a tapered sleeve 11 which permits a tight fit in the boiler tube regardless of the size thereof. The sleeve 11 is backed up by a nut 10 threaded on the pipe 12, the other end of the pipe being threadedly received by one of the openings in the four way pipe fitting 3. The pipe 12 may be bowed or otherwise shaped as at 13 to more readily accommodate the device to various positions or particular locations of tubes encountered during the boiler cleaning operation.

Fig. 2 shows a further modification of the invention. This arrangement is particularly adapted to clean vertical boiler tubes, as shown in dotted lines, from the bottom and comprises the handles 5, 6, coupling 2, valve 4, and four way fitting 3, which are common to both forms of the invention, and the arrangement of the blower head and supporting means as shown. A hollow casing 16 is provided with a movable rod 17 threaded to fit into an opening of the pipe fitting 3. The side of casing 16 has a slot 19 through which projects a boss 17 on the movable rod 15 to limit the vertical movement of the rod. A spring 21 is arranged in the casing 16 below the rod 15 to normally urge the rod upwardly while the blower is in operation. The blower 9 surrounded by the tapered sleeve 11 is secured to a pipe 8 threaded to fit into an opening in the fitting 3 and a nut 10 is employed to back up the sleeve 11. A threaded plug 22 is employed to close up the unused opening in the fitting which is adapted to receive the pipe 12 when converted into the attachment shown in Fig. 1.

The operation of the attachment shown in Figure 2 is thought to be clear but will be stated for convenience at this point. By means of handles 5 and 6 pipe 1 and consequently blower head 9, 11, and resilient support 16 are directed to the bottom of the boiler tube to be cleaned. The tapering sleeve permits a tight fit regardless of the size of

the tube within the limits of the sleeve and pipe 8 can be offset or otherwise shaped to reach all tubes whatever the locations. Sleeve 11 is tightly fitted into the boiler tube, the device being depressed against the pressure of spring 21 to accomplish the same. The tension of the spring 21 tends to normally maintain the sleeve 11 in working position independently of any force exerted on the handles 5 and 6. The steam or compressed air is expelled through suitably arranged openings in the blower head 9 arranged in the tapered sleeve 11 and is directed violently against the walls of the boiler tube thus effectively cleaning the same.

It is apparent that other modifications of the device can be obtained by rearranging the parts without departing from the spirit of the invention. I claim:

- 20 1. A boiler tube cleaner comprising a pipe, handles secured thereto, a coupling at the inlet end of the pipe, a fitting having a plurality of angularly arranged openings, an extension pipe fitted into one of the openings at an angle to said first pipe, a blower head secured to the other end of said extension pipe, a standard having one end fitted into an opening opposite said extension pipe, a plug fitted in the other opening, a casing slidably embracing the other end of the standard, a spring arranged between the end of the standard and the bottom of the casing, and a valve for controlling the discharge from said blower head.
- 25 2. A boiler tube cleaner comprising a pipe, handles secured thereto, a coupling at the inlet end of the pipe, a fitting having a plurality of angularly arranged openings at the other end of the pipe, an extension pipe fitted into one of the openings at a right angle to said first pipe, a blower head secured to the other end of said extension pipe, a standard having a foot at one end and having the other end fitted into an opening opposite said extension pipe and at right angles to said first pipe, a plug fitted in the other opening, a casing slidably embracing the foot end of the standard, a compression spring arranged between the foot of the standard and the bottom of the casing, and a valve for controlling the discharge from said blower head.

Dated the 17th day of August, 1927.

DAVID YOUNG.
